UNITED STATES PATENT OFFICE.

JOHN A. BRILL AND GEORGE MARTIN BRILL, OF PHILADELPHIA,
PENNSYLVANIA.

RAILWAY-CAR TRUCK.

SPECIFICATION forming part of Letters Patent No. 433,932, dated August 12, 1890.

Application filed October 2, 1888. Serial No. 286,958. (No model.)

To all whom it may concern:

Be it known that we, JOHN A. BRILL and GEORGE MARTIN BRILL, citizens of the United States, residing at Philadelphia, in the county 5 of Philadelphia and State of Pennsylvania, have invented certain new and useful Improvements in Railway-Car Trucks, of which the following is a specification.

Our invention has relation to independent rigid trucks for street-cars, or that form of trucks which, while rigidly secured to the car-body in contradistinction to pivoting the truck to the car-body, is removable therefrom, such as shown in Patent No. 425,653, 15 granted to us April 15, 1890; and it has for its object a construction of independent truck-frame wherein an electric or other motor may be mounted wholly upon the truck-frame, or partly thereon and partly upon the car-axles, 20 wherein a light-weight and separate axle-box frame is provided for supporting the fenders, track-brushes, track brake-shoes, and sand-boxes, and wherein a post form of pedestals may be used for the axle-boxes, said truck-frame being rigid and strong enough for all 25 conditions of service and readily attachable to and detachable from the car-body.

Our invention accordingly consists of the combinations, constructions, and arrangements of parts, as hereinafter described in 30 the specification, and pointed out in the claims, reference being had to the accompanying drawings, wherein—

Figure 1 is an elevation of an independent 35 rigid truck embodying our improvements and shown attached to the car-body framing or sill-pieces. Fig. 2 is a sectional elevation of part of one end of the car and brace-rods for connecting the ends of the car to the lower 40 chords or pedestal-connecting bars. Fig. 3 is an elevation, partly sectional and drawn to an enlarged scale, of part or one end of said truck. Fig. 4 is a side elevation of axle-box with part of truck-frame and a form of axle- 45 box-frame supports detached from the truck. Fig. 5 is a detail elevation, partly in cross-section, of the truck-frame upper and lower chords and connections; and Fig. 6 is a sectional elevation showing another form of axle- 50 box-frame support.

A represents the independent rigid or other truck-frame, composed of a top frame B, having side bars or chords b b , and end cross-bars b' , and, if desired, intermediate cross-bars b^2 , which are suitably secured together and may 55 be of any suitable material and of any suitable configuration in cross-section, as desired; but we prefer to make it of flat bar-iron, the parts of which are forged together to provide a frame B in one piece when completed. 60

To frame B are secured the axle-box pedestals or supports C, which may be of any suitable kind or make; but we prefer that form of same known as the "post form," and which is shown as consisting of grooved top 65 plates c , embracing the side bars or chords b of frame B, and having smooth openings near their ends for the passage of the upper ends of the posts c' , which post ends may be threaded and shouldered and screw into the 70 sides b of frame B, as indicated, and as fully shown, described, and claimed in another pending application filed by us of even date herewith, Serial No. 286,957. If desired, however, the posts c' may be secured to the frame 75 sides b in any other suitable way.

The axle-boxes D are provided with spring-seats d , through which the posts c' pass, and the latter are, if desired, provided with the main springs E and secondary top and bottom 80 springs e and e' , respectively, and suitable caps or plates are interposed between said springs, as fully set forth in said other pending application, or any other suitable arrangement of springs between the axle-boxes and 85 truck-frame may be substituted for that shown.

F F represent lower side bars or chords for the truck-frame, which chords may be connected to the axle-box pedestals, or the posts 90 c' of the latter may pass through and slide in openings in the chords F, as indicated. The end sections f of the chords F are preferably separate from the main sections f' , and are bolted thereto and to the frame B, so that the 95 main sections f' may be removable from the truck to admit of inserting the axle-boxes in position when building the truck and for dismounting the same for purposes of repairs or replacement. The main chord-sections f' 100

may be of any suitable form in cross-section; but we prefer to use the ordinary commercial angle-iron therefor and connect them by suitable corresponding or other cross-bars 5 f^2 , which cross-bars are preferably arranged or located near the transverse center of the truck-frame or between the wheels to afford a rigid and strong foundation for wholly supporting an electric or other motor thereon, 10 or for partly supporting it thereon and partly on the axles, as indicated at G, Fig. 1. If desired, the cross-bars f^2 may be connected to frame B and the motor secured thereto, as above described.

15 The lower chords F and the sides or chords b of frame B are near their transverse centers connected by V or other shaped brace-rods I and vertical pillars or posts i i, to prevent the truck-frame sagging or bending at its 20 transverse middle, and for economy of construction we prefer to secure the brace-rods I and posts i to said chords and the cross-bars f^2 to the lower chords F, as more plainly shown in Fig. 5, wherein are indicated clips 25 h, having bent ends h' secured to the lower side of the horizontal wing or top of the cross-bars f^2 , which bent ends h' are bolted, as indicated at h², to the vertical sides of the chord-sections f', and other corresponding clips h³ 30 are bolted to the upper side of the top of the cross-bars f^2 . Said clips h³ and the horizontal or upper sides of the chord-sections f' and the brace-rods I have openings through which the posts i pass, and all of said parts are firmly 35 bolted together and to the posts by means of collars i' and nuts i² on the lower ends of the posts i. The upper ends of the posts i are connected or secured to the frame chords or sides b, as shown, or otherwise, as desired.

40 The ends i³ i³ of the brace-rods I may be secured to the frame sides or chords b or to the opposing ends of the pedestal castings or plates c, as desired.

The brace-rods I may be in one piece or be 45 composed of separate rods, as indicated in Fig. 1 of the drawings.

When the truck A is used on summer-cars, or those having an extreme length, brace or truss-rods K, between or joining the ends of 50 the car and the chords or pedestal connecting bars F, are preferably employed, and the junction or coupling for the chords F and the brace-rods K may be of a construction as shown in our other aforesaid application, or 55 as shown in the drawings, wherein either the chord-sections f or f' are formed with an angularly-arranged pin or foot f⁵ for engagement with or insertion into the bore of the end of the tubular brace-rod K, as shown 60 more plainly in Fig. 2, the opposite end of said brace-rod sliding in tubular brackets k, secured to the ends of the car and being exteriorly threaded and provided with jam-nuts k' k², (see Fig. 2,) so that said pin-coupling f⁵, 65 between the braces K and chords F, may be made and disconnected by simply adjusting the jam-nuts k' k² and sliding the brace-rod

longitudinally to admit of easy removal of the truck from the car-body and of attachment thereto.

M represents the axle-box frame, which may be constructed of wood or partly of wood and iron, as desired, to make it of light weight, as it does not support the motor, and it has end fenders m. Frame M may be secured rigidly 70 to the axle-boxes or to depending or other located lugs d' thereon, as indicated in Fig. 6, or it may have any suitable form of spring-link or other support upon or connections with the axle-boxes. In Figs. 3 and 4 we 75 have shown modified forms of said spring-supports, wherein d² represent vertically-arranged tubular lugs secured to or forming part of the axle-boxes. These lugs may be located between the springs E and the axle-boxes forming an integral part of the spring-seats d, as indicated in Fig. 3, or located on the sides of the boxes near their outer ends, as illustrated in Fig. 4, or otherwise, as desired. Through these lugs d² pass bolts d³, 80 connected by flat metal bars d⁵, to which the frame M is secured in any suitable manner. The springs d⁴ for the bolts d³ may be arranged or located between the head of the bolts d³ and the top of lugs d², as indicated 85 to the left of Fig. 3, or be located within the bore of said lugs, as shown to the right of said figure.

The axle-box frame M, it will be observed, is independent of the truck-frame supporting the motor, and upon frame M may be located the track-brushes, track brake-shoes, and sand-boxes, as fully set forth in our aforesaid other pending application, or, if desired, the sand-boxes may be secured to 105 frame B or chords F.

If desired, the main section f' of the lower chords F of the truck-frame may be made sectional, as indicated at f⁶, Fig. 3, so that the ends of said sections bridging the axle-box 110 pedestals may be removed whenever it is desired to dismount the axle-boxes without necessitating removal of the brace-rods I and posts i. So, too, if desired, elastic buffers or 115 springs c⁵ may be placed on the posts c', between the axle-box spring-seats d and the lower chords F, to compensate for or take up the jolting vibrations of the wheels on the rails.

As the novel features of our improvements 120 may be greatly varied within the spirit of the invention, we do not confine ourselves to the same as shown and described.

What we claim is—

1. The combination of the upper longitudinal chords adapted to be rigidly secured to the car-body, and having pedestals squared thereon, the lower longitudinal chords extending approximately from end to end of and connected to the upper chords, truss or 130 brace rods and bolts connecting said upper and lower chords intermediate of the pedestals to form a truss, and cross-bars connecting said trusses, for the purpose set forth.

2. The combination of a rectangular frame, the sides of which form the upper chords of trusses on the sides of a truck, and having the pedestals secured and squared thereon, 5 the lower longitudinal chords connected together by cross-bars and extending from end to end of the upper chords, to which they are secured, and truss or brace rods and bolts connecting said upper and lower chords intermediate of the pedestals, for the purpose 10 set forth.

3. In a car-truck, the combination of axle-boxes having lugs d , spring-supported bars d^2 on said lugs, and frame M, secured to bars d^2 , substantially as set forth. 15

In testimony whereof we affix our signatures in presence of two witnesses.

JOHN A. BRILL.

GEO. MARTIN BRILL.
